SHEET-MATERIAL EXPANDER

George P. Knapp, Waban, Mass., assignor to Mount Hope Machinery Company, Taunton, Mass., a corporation of Massachusetts

Filed June 20, 1961, Ser. No. 129,927

19 Claims. (Cl. 26—63)

The present invention relates to sheet-material expanders and the like and, more particularly, to rotatable roller mechanism that provide a substantially infinite number of gentle spreading actions across the width of a sheet or web, such as a fabric material or the like, moving over the roller mechanism, in order to expand the sheet or web and thereby eliminate wrinkles, slack edges, baggy centers, loss of width in sheet processing, and automatically to provide a smooth full-width sheet or web.

Expander mechanisms of the above-described type have long been in use in textile mills and in other operations, and are described, for example, in United States Letters Patent No. 2,393,191, issued January 15, 1946. Because of the fine nature of certain fabrics and other materials, the expander rollers are often provided with smooth rubber or similar outer surfaces. There are certain fabrics or other sheets or webs, however, that do not require that the expander roller have such smooth surfaces for expanding the same. Rayon or nylon webs, as an illustration, which may be employed as relatively coarse tire reinforcements, may be expanded by a bowed expander roller constituted of interlocking, rotatable spools, successively aligned along the axis of the roller, and provided along the roller outer surface with longitudinally extending fins interlocking the successive spools and enabling free rotation thereof as the sheet or web is drawn thereover. Such a construction is advantageous when the web being handled is at a relatively high temperature, which would cause rapid deterioration of the covering of an expander, the outer surface of which is a sleeve of rubber or similar material. In the past, these longitudinally extending fins have been fabricated by setting them into recesses or grooves, formed within the periphery of the spools. Such structures, however, are rather costly to manufacture and, in addition, are subject to the very serious disadvantage that the adjacent ends of the spool fins that interlock are subject to a continual random rubbing contact that tends to sharpen the fins and thus ultimately, to damage the sheet or web material passing thereover, as the result of pinching, cutting or fraying action caused by the sharpened fin ends.

An object of the present invention, accordingly, is to provide a new and improved sheet-material-expander structure that shall not be subject to the above disadvantages but that, to the contrary, shall not only be of less costly construction, but shall inherently prevent the contacting and sharpening of the interlocking ends of the fins of the adjacent spools, and thus obviate damage to the sheet material expanded thereby.

A further object is to provide a new and improved expander of more general utility, also.

Still a further object is to provide a novel fin structure of the character described.

Other and further objects will be explained hereinafter, and will more particularly be pointed out in connection with the appended claims. In summary, however, the invention involves, in a sheet-material-expander, a longitudinally-extending channel member, substantially U-shaped in cross-section, having, preferably, substantially planar bottom and side walls, and provided at its ends with longitudinal side extension, the lower edges of which are disposed above the bottom channel wall. The side extensions at one of the ends of the

2

channel members are provided with buffer means, preferably in the form of buffer flanges extending laterally outward therefrom, that prevent contacting and consequent sharpening of the ends of the channel members.

5 The invention will now be described in connection with the accompanying drawings,

FIG. 1 of which is an isometric view of an expander channel member constructed in accordance with a preferred embodiment of the invention;

10 FIG. 2 is a similar view, illustrating a pair of adjacent spools, making up an expander roller, and provided with channel members of the type illustrated in FIG. 1;

FIG. 3 is a transverse section taken along the line 3—3 of FIG. 2, looking in the direction of the arrows;

15 FIG. 4 is a top elevation illustrating the expanding action of the expander roller of FIG. 2, upon a web of sheet material; and

FIG. 5 is a transverse section taken along the line 5—5 of FIG. 4, looking in the direction of the arrows.

20 Referring, first, to FIG. 4, a web of sheet material, such as, for example, the before-mentioned rayon or nylon tire reinforcing fabric, or the like, is shown at 1, proceeding in the direction of the arrow I, over a bowed expander roller, generally indicated by the reference numeral 2, and comprising a plurality of successive interlocking spool 2', 2", . . . 2'', mounted as free-wheeling rollers about a bowed stationary axle 4, FIG. 5.

25 The individual strands of the webs 1 will approach contact with the outer surface of the expander roller 2 at successively diverging angles on either side of the longitudinal center line of the web 1, as indicated by the arrows II. Upon contacting the freely rotating outer surface of the roller 2 at an infinite number of points, the web 1 will be generally spread across its width so that the fabric strands will proceed, to the left, beyond the expander roller 2, in substantially parallel lines, as shown by the arrows III. The fabric 1 has thus been expanded and smoothed out with an even width-wise tension that removes wrinkles, slack edges, baggy centers and other distortions.

30 In accordance with the present invention, the outer surface of the free-wheeling roller 2 is formed by a plurality of longitudinally-extending channel members of the type shown at 6 in FIG. 1. Each channel member is substantially U-shaped in cross-section, and is provided with a substantially planar bottom wall 8, conforming substantially to the cylindrical roller surface, and longitudinally-extending, substantially planar side walls 10. The bottom wall 8 may be welded or otherwise secured, as more particularly shown in FIGS. 3 and 5, to cylindrical spools or sleeves 12, thus obviating the necessity for pre-grooving the spool sleeves 12 and fitting fins therein, as in prior-art devices of this character, and thereby greatly simplifying the construction process.

35 45 55 60 65 70 At one end of each of the channel members 6, shown as the right-hand end in FIG. 1, the longitudinally-extending sides 10 of the channel member 6, which project substantially radially outward from the spools 12, are extended longitudinally beyond the bottom substantially planar wall 8, as shown at 10'. Similar longitudinal side-wall extensions 10" are provided at the other or left-hand end of the channel member 6, as shown in FIG. 1, with the bottom edges of the extensions 10" also disposed above the bottom channel wall 8. In the case of the extensions 10", however, buffer means are provided, preferably in the form of buffer flanges 14 that extend laterally outward from the side extensions 10", and are of length somewhat less than one-half the width of the channel member 6, as measured between the longitudinal side edges 10, for reasons later described.

As more particularly shown in FIGS. 2 and 3, channel members 6 of the type described in connection with the

embodiment of FIG. 1, are successively distributed about the cylindrical peripheral surface of each spool 12, with the extensions 10' of the channel members 6 interlocking with the extensions 10" of the corresponding channel members 6 of adjacent spools. Thus, the free ends 10' of the longitudinal side walls 10 of the channel members 6 of the spool 2' are interlocked between the flanges 14 of the free ends 10" of the corresponding channel members of the adjacent spool 2", with each flange 14 disposed between a pair of side extensions 10' of channel members of the adjacent spool 2'; and so on, for the remaining spools of the expander roller 2. As a result of this construction, the free ends 10' of the side walls 10 of the channel members of the spool 2' are coupled to the side wall extensions 10" of the channel members of the adjacent spool, but are prevented, by the buffering action of the flanges 14 of the corresponding channel members 6 of the adjacent spool 2", from contacting the free ends 10" of such corresponding channel members 6, thus preventing any sharpening of adjacent channel-member edges and preventing consequent damage to the web that would result from such sharpening, as before explained.

In order to limit the amount of play in the free-wheeling successive spools 2', 2", . . . 2", making up the outer sleeve of the expander roller 2, and in order to provide for the symmetrical construction above-described, the length of each buffer flange 14, as measured in a lateral direction substantially parallel to the plane of the bottom walls 8 of the channel members, will be somewhat less than one-half the width of the channel members between the side walls 10 thereof, as before mentioned.

It will be evident that it is not necessary, though it is deemed preferable, to employ the particular geometrical configuration of substantially planar buffer flanges 14, and that, similarly, the shape of the channel members may deviate from the particular geometrical configuration illustrated and described; but in all cases, the channel members will be substantially U-shaped in cross-section.

Further modifications will occur to those skilled in the art, and all such are considered to fall within the spirit and scope of the invention, as defined in the appended claims.

What is claimed is:

1. A longitudinally extending channel member for use in a sheet-material-expander, the said member being substantially U-shaped in cross-section and provided at its ends with longitudinal side extensions, with the side extensions at one of the ends being provided with buffer means extending laterally outward therefrom.

2. A longitudinally extending channel member for use in a sheet-material-expander, the said member being substantially U-shaped in cross-section having bottom and side walls and provided at its ends with longitudinal side extensions, with the side extensions at one of the ends being provided with buffer flanges extending laterally outward therefrom.

3. A longitudinally extending channel member for use in a sheet-material-expander, the said member being substantially U-shaped in cross-section having substantially planar bottom and side walls and provided at its ends with longitudinal side extensions the lower edges of which are disposed above the bottom channel wall, the side extensions at one of the ends being provided with buffer means extending laterally outward therefrom.

4. A longitudinally extending channel member for use in a sheet-material-expander, the said member being substantially U-shaped in cross-section having substantially planar bottom and side walls and provided at its ends with longitudinal side extensions the lower edges of which are disposed above the bottom channel wall, the side extensions at one of the ends being provided with buffer flanges extending laterally outward therefrom.

5. A longitudinally extending channel member for use in a sheet-material-expander, the said member being substantially U-shaped in cross-section having bottom and

side walls and provided at its ends with longitudinal side extensions, with the side extensions at one of the ends being provided with buffer flanges extending laterally outward therefrom a distance somewhat less than one-half the width of the channel member between its sides.

6. A longitudinally extending channel member for use in a sheet-material-expander, the said member being substantially U-shaped in cross-section having substantially planar bottom and side walls and provided at its ends with longitudinal side extensions the lower edges of which are disposed above the bottom channel wall, the side extensions at one of the ends being provided with buffer flanges extending laterally outward therefrom a distance slightly less than one-half the width of the channel member between its sides.

7. Three coupled longitudinally extending channel members for use in a sheet-material-expander, each of the said members being substantially U-shaped in cross-section having bottom and side walls and each provided at its ends with longitudinal side extensions, with the side extensions at one of the ends of each member being provided with buffer means and with the buffer means of two of the channel members being disposed on opposite sides of one of the side extensions at the other end of the third channel member, the said two channel members being carried by a support and said third channel member being carried by a further support.

8. Three coupled longitudinally extending channel members for use in a sheet-material-expander, each of the said members being substantially U-shaped in cross-section having bottom and side walls and each provided at its ends with longitudinal side extensions, with the side extensions at one of the ends of each member being provided with buffer flanges extending laterally outward therefrom and with buffer flanges of two of the channel members disposed on opposite sides of one of the side extensions at the other end of the third channel member, the said two channel members being carried by a support and said third channel member being carried by a further support.

9. Three coupled longitudinally extending channel members for use in a sheet-material-expander, each of the said members being substantially U-shaped in cross-section having substantially planar bottom and side walls and each provided at its ends with longitudinal side extensions the lower edges of which are disposed above the bottom channel wall, the side extensions at one of the ends of each member being provided with buffer means, and with the buffer means of two of the channel members being disposed on opposite sides of one of the side extensions at the other end of the third channel member, the said two channel members being carried by a support and said third channel member being carried by a further support.

10. Three coupled longitudinally extending channel members for use in a sheet-material-expander, each of the said members being substantially U-shaped in cross-section having substantially planar bottom and side walls and each provided at its ends with longitudinal side extensions the lower edges of which are disposed above the bottom channel wall, the side extensions at one of the ends of each member being provided with buffer flanges extending laterally outward therefrom, and with buffer flanges of two of the channel members disposed on opposite sides of one of the side extensions at the other end of the third channel member, the said two channel members being carried by a support and said third channel member being carried by a further support.

11. A sheet-material-expander component comprising a longitudinally extending cylindrical member provided along its surface with a plurality of successively disposed longitudinally extending channel members each substantially U-shaped in cross-section having bottom and side walls and provided at its ends with longitudinal side ex-

tensions, with the side extensions at one of the ends of each member being provided with buffer means.

12. A sheet-material-expander component comprising a longitudinally extending cylindrical member provided along its surface with a plurality of successively disposed longitudinally extending channel members each substantially U-shaped in cross-section having bottom and side walls and provided at its ends with longitudinal side extensions with the side extensions at one of the ends of each member being provided with buffer flanges extending laterally outward therefrom.

13. A sheet-material-expander component comprising a longitudinally extending cylindrical member provided along its surface with a plurality of successively disposed longitudinally extending channel members each substantially U-shaped in cross-section having substantially planar bottom and side walls and provided at its ends with longitudinal side extensions the lower edges of which are disposed above the bottom channel wall, the side extensions at one of the ends of each member being provided with buffer means.

14. A sheet-material-expander component comprising a longitudinally extending cylindrical member provided along its surface with a plurality of successively disposed longitudinally extending channel members each substantially U-shaped in cross-section having substantially planar bottom and side walls and provided at its ends with longitudinal side extensions the lower edges of which are disposed above the bottom channel wall, the side extensions at one of the ends of each member being provided with buffer flanges extending laterally outward therefrom.

15. A sheet-material-expander comprising a plurality of adjacent free-rotating coupled longitudinally extending cylindrical members each having along its surface a plurality of successively disposed longitudinally extending channel members each substantially U-shaped in cross-section having bottom and side walls and each provided at its ends with longitudinal side extensions, with the side extensions at one of the ends of each channel member being provided with buffer means, and with the buffer means of the channel members of each cylindrical member being disposed between the side extensions at the other end of the corresponding channel members of an adjacent cylindrical member, in order to interlock side extensions at the said other end of each cylindrical member between the buffer means of the corresponding channel members

of an adjacent cylindrical member, the axis of each cylindrical member being disposed at a small angle with respect to the axis of adjacent cylindrical members.

16. A sheet-material-expander comprising a plurality of adjacent free-rotating coupled longitudinally extending cylindrical members each having along its surface a plurality of successively disposed longitudinally extending channel members each substantially U-shaped in cross-section having bottom and side walls and provided at its ends with longitudinal side extensions, with the side extensions at one of the ends of each channel member being provided with buffer flanges extending laterally outward therefrom, and with the buffer flanges of the channel members of each cylindrical member being disposed between the side extensions at the other end of the corresponding channel members of an adjacent cylindrical member, in order to interlock side extensions at the said other end of each cylindrical member between the buffer flanges of the corresponding channel members of an adjacent cylindrical member, the axis of each cylindrical member being disposed at a small angle with respect to the axis of adjacent cylindrical members.

17. A sheet-material-expander as claimed in claim 16 and in which the lower edges of the longitudinal side extensions of the channel members are disposed above the bottom channel wall thereof.

18. A sheet-material-expander as claimed in claim 16 and in which the successively coupled cylindrical members are disposed along a bowed axis.

19. A sheet-material-expander as claimed in claim 16 and in which the width of each buffer flange is slightly less than one-half the width of the corresponding channel member between its longitudinal sides.
